UNITED STATES PATENT OFFICE

148,444

DESIGN FOR AN OUTBOARD POWER UNIT FOR GLIDERS

Elton H. Rowley, Wichita, Kans.

Application May 31, 1946, Serial No. 130,478

Term of patent 14 years

(Cl. D71—1)

To all whom it may concern:

Be it known that I, Elton H. Rowley, a citizen of the United States, residing at Wichita, Kansas, have invented a new, original, and ornamental Design for an Outboard Power Unit for Gliders, of which the following is a specification, reference being had to the accompanying drawing, forming a part thereof.

Figure 1 is a top plan view of an outboard power unit for gliders, embodying the new design;

Figure 2 is a front elevational view;

Figure 3 is a side elevational view; and

Figure 4 is a three-quarter front isometric view of the same power unit illustrating the manner of its attachment to a glider, the glider being shown in broken lines, and for illustrative purposes only.

I claim:

The ornamental design for an outboard power unit for gliders, substantially as shown and described.

ELTON H. ROWLEY.
